WILLIAM H. WEEKS, OF PHILADELPHIA, PENNSYLVANIA.

MACHINE FOR COATING CONFECTIONERY.

No. 866,702.

Specification of Letters Patent.

Patented Sept. 24, 1907.

Application filed February 21, 1907. Serial No. 358,632.

To all whom it may concern:

Be it known that I, WILLIAM H. WEEKS, a citizen of the United States, residing in the city of Philadelphia, State of Pennsylvania, have invented certain new and useful Improvements in Machines for Coating Confectionery, of which the following is a full, clear, and exact description, reference being had to the accompanying drawings, forming a part of this specification.

My invention relates to machines for coating cream drops, candy cores or other solid filling material, with chocolate or other soluble coating substance which will solidify on exposure to air; and has for its objects a carrying forward and improvement of the machine shown and described in U. S. Letters Patent granted 10 to me May 8, 1906, No. 820,030, wherein is described a machine for coating confectionery, employing a detachable dipping tray, said machine operating on the principle of a horizontally-inclined movement of the dipping-frame through the solution tank, effecting a 15 downwardly-inclined, sidewise dipping of the core-supporting tray therein. Said method of dipping (as contra-distinguished from a perpendicular dipping) obviates the necessity for any cover for the detachable core-holding tray, enables the supporting and carrying 20 of a series of such trays, instead of a single tray at each dipping as heretofore, enables a detached tray to be operatively supported on the dipping frame, during dipping, solely by gravity aided by the weight of the tray; and finally, by appropriate construction and ar- 25 arrangement of the tray-receiving frame relatively to the solution tank and the moving dipping frame and its actuating devices, each tray, in the series, is, after dipping, brought into horizontal parallelism with said tray-receiving frame, and automatically discharged 30 thereon by and from the moving dipping frame. The machine described in said Letters Patent comprises elements so operating, and I refer to said Letters Patent for a full disclosure thereof.

My present invention is predicated thereon and consists first in improved means to guide the movable dipping frame through the solution tank, and secondly in the provision of a tray-feeding device at the receiving end of the tank, operating to support, temporarily, each core-filled tray as placed thereon by the operator, 40 with means between such supporting feed-device and the dipping frame whereby the tray is released from its support at the proper time and automatically caught by and received upon the moving dipping frame, and by the latter carried through the solution, as aforesaid, 45 and finally is brought, as before, into parallelism with and automatically discharged upon the receiving frame at the delivery end of the machine.

In the drawings illustrating my present invention:— Figure 1 is a vertical section through the longitudinal center of the solution tank, showing in elevation one of the opposite-disposed pair of guide-brackets for the

movable dipping frame, the actuating means for the latter, and the tray-receiving frame at the discharge end of the tank; all other parts being removed for the sake of clearness. Fig. 2 is a side elevation of the machine, with my new automatic tray-support at the feed end of the tank. Fig. 3 is a detached view of the latter and of its coating elements on the dipping frame, the parts being shown in initial and locked position; and Fig. 4 is a detached part of the same elements in released position, showing the tray caught by the moving dipping frame.

Referring now to said drawings: A is an open-topped tank to receive the coating solution; it is substantially an oblong rectangle in planular outline; its double bottom provides a hollow space *a* containing perforated pipes *a'*, with inlet pipe *b* and discharge pipe *b'* to supply hot water thereto to maintain the chocolate or other solution in proper liquid condition suitable for coating purposes.

The tank is constructed with a horizontally-inclined bottom for the purpose primarily of causing a gravity flow of the liquid solution, and drippings, from the shallow or tray-discharging end towards the tray-receiving end, to insure a dipping movement below the surface of the solution, and for the further purpose of bringing the tray, at the discharge end, above the surface of the liquid and in horizontal parallelism with the tray-receiving mechanism upon which it is automatically discharged by the movable dipping-frame *d*.

The solution tank is suitably supported above the factory floor, as by standards *B*, *B'*, arranged in pairs at the opposite ends of the tank; the standards *B'*, *B* at the shallow end being utilized as bearings for the main driving-shaft *b* which extends through said standards. The machine is otherwise provided with like actuating mechanism, as in my former patent referred to, for operating the endless-chain dipping-frame which carries the detachable core-supporting trays.

The movable dipping-frame consists of the oppositely-disposed parallel endless chains *d*, *d'*, connected at suitable intervals by pairs of cross-bars *r*, preferably in the form of angle-irons, which are thus adapted to support the opposite longitudinal edges of a core-holding tray *5*. Each endless chain of this dipping-frame is driven by a pair of sprocket-wheels *d* and *m*; the smaller sprocket wheels *d*, *d'* are mounted on the driven shaft *c*, at the shallower end of the tank, while the larger sprockets *m*, *m'*, are arranged at the receiving end of the tank, and mounted on the shaft *n* journaled at each end in a hub set into the inner face of each vertical wall of the tank, as described in my former patent. The two pairs of sprocket wheels are so proportioned in size, and arranged, relatively to the deep and shallow parts of the tank, that a core-holding tray in initial position on the dipping-frame, ready to be dipped, will be slightly above the solution in the

tank; while at the point above the smaller sprocket wheel, a core-holding tray which has been dipped and is resting on the endless chain dipping-frame, back of the angle-iron cross-bar r provided therefor and 5 ready to be discharged, will then have its front edge resting coincident and in the same horizontal plane with the receiving frame N so that as such cross-bar r , back of the tray, carried by the moving dipping-frame, begins to descend again, the detached tray will be 10 automatically pushed forward by said bar and slid onto the said receiving frame, and so on for each tray in the series as it reaches that point.

The series of angle-iron cross-bars r connecting the endless chains d^3 d^3 , arranged in pairs at suitable intervals thereon, are well adapted to support and maintain in position solely by gravity and their weight the filled core-holding trays during the passage of both 15 through the coating solution in the tank and freely permit the tray to be slid off the same onto the receiving-frame, but they perform an additional function, namely, the vertical portion of the angle-bar r , carried 20 forward by the moving dipping-frame, operates by a pushing contact against the detached tray to slide it off the dipping-frame and onto the receiving frame N , 25 while the next succeeding tray brought to the same position by the dipping-frame displaces the preceding tray on the receiving frame, pushing it forward to the pivoted discharge end thereof, as in said former patent described.

30 Guiding devices to direct the endless chain dipping-frame in the requisite path of movement through the tank, consist of a pair of brackets S , S , shown in detached elevation in Fig. 2, and in position in the tank, in Fig. 1. These brackets comprise an arm s , vertically 35 slotted as at s' , with a long curved bearing face s^3 , and are secured in a depending position to the vertical walls of the tank by set screws s^2 or equivalent means, passing through the slot and hence vertically adjustable. The brackets are mounted at such position on 40 the walls of the tank as to abut midway of the sprocket wheels d^2 and m , and to bring the chain dipping-frame, at the center of its plane of movement, below the same in about the same plane with the shaft n upon which the larger sprocket wheel is mounted, so as to insure 45 a dipping of the tray below the solution in the tank. Each opposite chain of the dipping frame is thus guided by and carried below the curved face of said guiding bracket S , and hence sufficiently near the base of the tank and below the solution therein.

50 The core-receiving tray 5 is an open wire basket, with core-holding pockets formed by bending the cross-wires at suitable intervals. These are well known in the art, examples of which will be found in German patent to Reiche No. 18943 dated December 11, 1881 55 and numerous U. S. patents since then, notably U. S. Patents No. 684,147 dated October 8, 1901 and No. 828,694 dated August 14, 1906, both granted to me. For use with my present machine herein described the essentials of such a tray are that it shall have core-holding 60 pockets and a frame that is so far open that when dipped in the chocolate solution the cores will be coated and the surplus solution drip through the interstices of the tray into the tank as the tray emerges from the solution, and that, as to size and shape, it shall be 65 capable of resting, by gravity, on the chain dipping-

frame, with the frame wires of its long sides resting on and between the pairs of angle-bars r thereon.

At the shallow end of the tank, which is the tray-discharging end, is mounted the tray-receiving frame N so located as to co-act with the movable dipping-frame, in order that as each detached tray resting on the latter between any pair of supporting bars r thereon, is carried thereby through the solution, it emerges therefrom in such manner that one of its longitudinal edges is brought into coincidence with the adjacent 75 edge of the receiving-frame, hence as the dipping-frame continues to move, the angle-iron bar fast thereon and supporting the rear edge of the tray, operates to automatically push the tray off the frame and directly onto the receiving frame N . The number of such sets 80 of tray-supports is governed by the operative length of the dipping frame; and, as shown in the drawings, three such sets, and three trays, may rest on the upper and forward-moving part of the frame, at the same time.

The tray-receiving frame and its adjunctive parts 85 whereby it is given a vertical vibratory movement, between the reception of each tray thereon, to shake off the surplus coating from the cores, the means to produce such vibratory movement, and the rearward hinged extension of the receiving frame to enable it to 90 be reversed to discharge the tray contents, are the same as in my former patent No. 820,030 and need not be further described. But in the machine of that patent, the trays, which are manually filled with cores to be coated, were placed by the operator directly on the 95 dipping-frame between the nearest set of angle-bars r , to accomplish which the machine was tripped or stopped.

The most important feature of my present invention is the provision of means to automatically feed the 100 filled trays to the moving dipping-frame, and without stopping the continuous operation of the machine; and my invented mechanism for that purpose, shown in plan view, in place on the solution tank, in Fig. 3, and in detail views in Figs. 4 and 5 I will now describe.

At the deep or receiving end of the tank A is fixedly 105 mounted a pair of upright standards 2 of such form at top, as at 3, to support in an inclined direction (see Figs. 4 and 5), a pair of suitable frame bars, preferably angle-iron bars 5^a , on the upright and basal portions of which is supported and guided the opposite lateral frame bars of the tray 5 . Between these standards 2 is fixedly mounted a connecting cross-rod 4 which also 110 operates as a hinge bearing for a latch finger 6 which is pivotally mounted, about midway of its length, on said cross-rod 4 , and operates both as a locking and a releasing trigger. The lower end of this latch finger 6 extends downward to a point over the dipping-frame d^3 where, in normal position, it will be struck by the passing angle-bars r on the movable dipping frame. The 115 upper end of this latch finger 6 is sufficiently curved or provided with a bend 9 at the extreme end, to operate as a hook to engage the adjacent frame wire of the tray 5 , and normally hold it on the feeding-frame bars 5^a until released therefrom. To maintain such hinged 120 finger 6 in such normal inclined position, its lower end is made heavier than its upper end, or in lieu thereof a spring 7 may be twisted around the cross-rod 4 , with its opposite ends bearing against the upper end of the latch finger and the rear edge wall of the tank, respec- 125 130

tively; but I prefer to make the lower end of the finger heavier or weighted, for maintaining the finger in the required inclined position normally.

The tray being filled with cores to be coated is placed by the operator on the feeding-frame, with its rear frame wire engaging the hooked end of the pivoted latch-finger 6, as shown in Fig. 4; and this without stopping the operation of the machine. The dipping-frame α^2 being in motion, the angle-iron cross-bar r thereon will slidingly collide with and lift the adjacent lower end of the pivoted latch-bar 6, thereby releasing it from engagement with the tray 5, as shown in Fig. 5; and the released tray will thereupon slide by gravity down the inclined feeding-frame and be deposited directly upon the traveling dipping-frame, its rearward edge falling into position over the particular actuating bar 7, the tray coming to a stop on the dipping-frame between said actuating bar r and the next forward reversely-set angle-bar r on the dipping-frame, and so on as respects each tray placed on the feeding-frame; the trays being carried forward thereby, through the solution in a sidewise direction as shown in Fig. 1, and finally lifted out of the solution by the dipping frame and deposited automatically on the receiving-frame N, as shown in Fig. 6, at the opposite and discharge end of the machine.

I do not wish to limit myself to the particular details of the tray-feeding mechanism, as it is obvious that some of the elements may be substituted by equivalents, but the essential principle thereof is embodied in an inclined tray-feeding frame, adapted to support a tray temporarily held thereon by engaging devices, and to slidingly discharge it therefrom automatically by and onto the passing dipping-frame by engagement therewith of tray-holding and supporting devices thereon adapted to receive it.

Having thus described my invention, I claim as new and desire to secure by Letters Patent:—

1. In a machine for coating cores by a sidewise dipping, comprising a suitable solution receptacle, an endless chain dipping-frame, means to actuate the same, and a receiving frame adapted to automatically receive thereon a detached core-holding tray delivered to it by said dipping-frame after dipping; of means to direct the path of movement of the dipping-frame through the solution recep-

tacle in a downwardly-inclined and then in an upwardly-inclined horizontal direction, said means consisting of a pair of oppositely-disposed sector-shaped brackets mounted in a depending position on the opposite vertical walls of the solution receptacle, said brackets having curved guiding faces adapted to direct the forward path of movement of the dipping-frame. 50

2. In a machine for coating cores by a sidewise dipping, comprising a suitable solution receptacle, a movable dipping-frame adapted to operatively support a detached core-holding tray, means to direct the path of movement of said dipping-frame through the solution receptacle in a downwardly-inclined and then an upwardly-inclined horizontal direction, with means to receive the tray discharged by the dipping-frame, of means to automatically feed the tray to the movable dipping-frame, said means consisting of a tray-feeding-frame mounted in a downwardly-inclined position relatively to the receiving end of the solution tank, means to normally hold the tray on said feeding-frame, and means actuated by the movable dipping-frame to release the tray from said inclined tray-feeding frame. 60

3. In a machine for coating cores by a sidewise dipping, comprising a suitable solution tank, a movable dipping-frame adapted to operatively support a detached core-holding tray, means to direct the path of movement of said dipping-frame through the solution in a downwardly-inclined and then an upwardly-inclined horizontal direction, with means to receive the tray discharged by the dipping-frame, of means to automatically feed the tray to the movable dipping-frame, said means consisting of a pair of upright standards, a pair of tray-supporting frame-bars mounted thereon in an inclined position over the tank, a connecting cross-rod between said standards, a latch-finger pivotally mounted intermediate its length 80 on said cross-bar, with means to maintain said latch-finger in an inclined position with one end thereof adapted to engage a tray on said frame-bars and the other end to be tripped by a tray-supporting bar on the dipping-frame. 75

4. In a machine for coating cores by a sidewise dipping, the combination with a suitable solution tank, and a movable dipping-frame operatively supported and actuated therein in a horizontally-inclined direction, with means to support a core-holding tray thereon, of tray-feeding 90 and tray-receiving devices at the respective opposite ends of the solution tank, adapted to be actuated by said dipping-frame and operating to automatically deliver and discharge a tray to and from said frame. 95

In testimony whereof, I have hereunto affixed my signature this third day of January A. D. 1907.
